CLAIM

An ornamental design for a smoke exhaust hood for a tilting furnace, as shown and described.

DESCRIPTION

FIG. 1 is a front view of a smoke exhaust hood for a tilting furnace, according to the new design.

FIG. 2 is a top plan view thereof.

FIG. 3 is a right side view thereof, the left being a mirror image.

FIG. 4 is a rear view thereof.

FIG. 5 is a bottom view thereof; and,

FIG. 6 is another right side view of the smoke exhaust hood, according to the design shown in FIG. 1, with an environmental tilting furnace for clarity of disclosure.

The elements shown in broken lines depict environmental subject matter only and form no part of the claimed invention.
